UNITED STATES PATENT OFFICE.

OTTO L. RAABE, OF JERSEY CITY, NEW JERSEY, ASSIGNOR TO R. HOE AND CO., OF NEW YORK, N. Y., A CORPORATION OF NEW YORK.

DRIVING MECHANISM FOR MULTICOUPLE PRINTING-MACHINES.

1,356,171.

Specification of Letters Patent. Patented Oct. 19, 1920.

Application filed January 2, 1920. Serial No. 349,010.

To all whom it may concern:

Be it known that I, OTTO L. RAABE, a citizen of the United States, residing at Jersey City, county of Hudson, and State of New Jersey, have invented certain new and useful Improvements in Driving Mechanism for Multicouple Printing-Machines, fully described and represented in the following specification and the accompanying drawings, forming a part of the same.

This invention relates to certain improvements in driving mechanism for rotary printing machines, and particularly to that class of machines employing a plurality of printing couples which are spaced apart or separated from each other, as for instance, such a machine as is shown in my co-pending application Serial No. 143,584, filed January 22, 1917.

In rotary web printing machines, particularly in machines printing several pages wide, the cylinders are very heavy, and where such cylinders are driven directly through gears thereon from the main driving shaft, the weight of the cylinders tends to wear down and deepen the teeth of the driving gears, thus injuring the gears and causing an improper relation between the driving and driven, elements. Furthermore, it is desirable in this class of machines that the printing couples be separated from each other so as to have a clear side, that is, with the inking mechanism arranged inside the couples, so that a web can be led through the couples from the clear side of the couples around the inking mechanism.

It is the object of the present invention to produce a drive whereby a plurality of spaced printing couples may be driven from the distributing cylinders of the couple, so that the couples are free of the gears on the main driving shaft, the distributor being arranged so that any down wear due to the weight of the printing couple does not interfere with the proper mesh of the gears.

It is a further object of the invention to produce a driving mechanism in which the distributing cylinders for a plurality of couples are so arranged that a plurality of distributors, as two, may be driven from the same shaft.

With this and other objects not specifically referred to in view, the invention consists in certain novel arrangements shown in

the accompanying drawing, in which the figure is an end elevation of so much of a multicouple rotary printing mechanism as is necessary to an understanding of the invention.

Referring now to this drawing, the invention is illustrated as embodied in a mechanism including a plurality of printing couples which may be, as shown, printing and perfecting couples. These couples will be so arranged with respect to their inking mechanisms that they will have a clear side, so that a web can be rotated through them from the clear side. Preferably, furthermore, the couples will be arranged in staggered or off-set relation vertically to each other, with the printing cylinders on the outside and the respective inking mechanisms in line above each other on the inside of the cylinders, this arrangement permitting the couples and their inking mechanisms to be arranged in a small space and permitting the two couples to be driven from the distributors of their inking mechanism by a single shaft.

In the particular construction shown, there is provided a rotary printing couple having a plate cylinder 1, and an impression cylinder 2, mounted in any suitable framing 3, the impression cylinder being preferably located vertically below the plate cylinder. This printing couple includes an inking mechanism comprising a fountain 4, distributing cylinder or drum 5, and form rolls 6, and this mechanism is arranged on the inside, or as shown at the left of the plate cylinder 1, and so that the axes of the plate cylinder 1 and distributing cylinder 5 are substantially in horizontal alinement.

A second printing couple, which is in the present instance, a perfecting couple, is mounted suitably in framing 3 and includes a plate cylinder 7 and impression cylinder 8. This couple is inked from a fountain roll 9 and distributor cylinder or drum 10 and form rolls 11. The inking mechanism for this couple is arranged as shown at the right of the printing cylinders so as to leave the printing cylinders on the outside with the axes of the plate cylinder 7 and distributor 10 in substantial horizontal alinement. The couples 1, 2, 7, 8, are thus in staggered or off-set relation vertically to each other and each on the outside of their respective ink-

ing mechanisms which are arranged above each other, and the distributor 5, 10 are arranged so that their axes are in substantially the same vertical line.

- 5 In accordance with the invention, one member of each of the couples, 1, 2, 7, 8 is driven from the distributing cylinder of the inking mechanism of the couple, and in the best constructions, these distributing cylinders are driven by a common shaft from the main driving shaft of the machine.

While the specific arrangement for effecting this may be somewhat varied, in the particular construction illustrated, there is 15 provided a vertical shaft 12, which at its lower end is provided with a bevel gear 13 meshing with a bevel gear 14 on the main power shaft 15 of the machine. This shaft 12 near its lower end is provided with a 20 bevel gear 16, which meshes with a bevel gear 17 carried on the end of the shaft 18 of the distributor 5, through which this distributor is driven. The form cylinder 1 is driven from the distributor 5 through a 25 gear 19 carried on the form cylinder shaft which meshes with an intermediate gear 20, which in turn meshes with a gear 21 on the shaft 18 of the distributor.

At its upper end the shaft 12 has fast 30 thereon a bevel gear 22, which meshes with a bevel gear 23 carried on the shaft 24 of the distributor 10, the distributor thus being driven from the shaft 12. The form cylinder 7 is driven from the distributor 10 by a 35 gear 25 carried on the form cylinder shaft which meshes with an intermediate 26, which in turn meshes with a gear 27 on the shaft of the distributor 10. When the form member of the couple is driven from the 40 shaft 12, the impression cylinders are geared to the form cylinders and driven therefrom.

With this construction a very simple and efficient drive has been provided for multi-couple machines where the couples are 45 spaced apart and one in which the couples are so driven from the distributor that they are free of the gears on the main power shaft of the machines, and the driving connections for the couples are such that any 50 sagging of the couples does not injure or effect the drive.

While the particular type of gear shown and described is effective, it will be understood that as to specific details the gears 55 may be varied without departing from the invention and the invention is not limited to the exact arrangement shown and described.

What I claim is.

- 60 1. In a driving mechanism for multi-couple rotary printing machines, the combination with spaced printing couples, of inking mechanisms therefor, which inking mechanism includes a distributing cylinder 65 or drum, and means for driving one mem-

ber of each of the printing couples from the distributing cylinder of its inking mechanism.

2. In a driving mechanism for multi-couple rotary printing machines, the combination with a pair of printing couples and inking mechanism for each couple including a distributing cylinder, the distributing cylinders being in substantially the same vertical plane, a power shaft, a shaft driven therefrom, connections from the second shaft to the distributing cylinders for driving them, and driving connections from each distributing cylinder to one member of the printing couples. 70

3. In a driving mechanism for rotary printing machines, the combination with a pair of spaced printing couples, inking mechanism for each couple including a distributing cylinder, each of said distributing cylinders being substantially in line horizontally with one member of the couple and vertically with each other, a power shaft, a shaft driven therefrom, driving connections for the distributing cylinders from the 80 second shaft, and driving connections from the distributing cylinders to one member of the couples. 85

4. In a driving mechanism for printing machines, a vertically arranged printing couple including a form and impression cylinder with the impression cylinder below, an inking mechanism including a distributing cylinder horizontally in line with the form cylinder, a second vertically arranged printing couple including a form and impression cylinder with the impression cylinder below, an inking mechanism therefor including a distributing cylinder in line horizontally with the form cylinder, a vertical shaft, gear connections between the shaft and both distributing cylinders, a power shaft, and gear connections between the vertical shaft and power shaft. 95

45 5. In a driving mechanism for printing machines, the combination of a printing couple, a second printing couple in off-set relation thereto, inking mechanisms on the inside of each couple, each inking mechanism including a distributing cylinder, a vertical shaft between the couples and common to the distributing cylinders, means for driving the shaft, and connections between the distributing cylinders and one member 100 of each of the couples. 105

6. In a driving mechanism for multi-couple printing machines, the combination of a plurality of spaced printing couples, separate inking mechanisms therefor, and means for driving one member of each of 115 the printing couples from a member of its inking mechanism. 120

In testimony whereof I have hereunto set my hand.

OTTO L. RAABE.
